UNITED STATES PATENT OFFICE.

RICHARD LIEBAU, OF NEW HAVEN, CONNECTICUT, ASSIGNOR TO THE WESTINGHOUSE AIR SPRING COMPANY, A CORPORATION OF PENNSYLVANIA.

MAGNETIC SPRING.

1,395,437.

Specification of Letters Patent.

Patented Nov. 1, 1921.

Application filed February 26, 1919. Serial No. 279,430.

To all whom it may concern:

Be it known that I, RICHARD LIEBAU, a citizen of the United States, and a resident of New Haven, in the county of New Haven and State of Connecticut, have made a new and useful Invention in Magnetic Springs, of which the following is a specification.

This invention relates to vehicle springs and more particularly to supplemental springs adapted to be used in series with the steel springs of motor vehicles.

It has been customary for some time to equip motor vehicles with four supplemental springs operating in series with the steel springs of the vehicle, in resiliently supporting the load platform. Air springs of the Westinghouse type have been used for this purpose as well as steel coil springs.

An object of this invention is to provide magnetic means capable of being used in series with the vehicle steel springs to resiliently support the load platform.

This, as well as other objects, I attain in the device described in the specification and illustrated in the drawings accompanying and forming a part of this application.

In the drawings, Figure 1 is a view in sectional elevation of one of the magnetic devices embodying this invention. It will be understood that such device will be used adjacent each corner of the load platform of the vehicle and arranged and connected so as to operate in series with the vehicle steel springs.

Fig. 2 is a fragmentary view in sectional elevation on an enlarged scale of the switches forming a part of the device of Fig. 1 and Fig. 3 is a diagrammatic illustration of the switches and coils which operate with the floating core in supporting the load platform.

Figs. 4 and 5 are views in sectional elevation showing modified arrangements of the coils.

The device consists of a support member 4 secured to the load platform of the vehicle by means of a bracket 5. The support member is bored out to form a cross head guide and within this a cross head 6 is arranged to reciprocate. The outward movement of the cross head is limited by means of a stop

7 which at the limit of the outward stroke contacts with a shoulder or flange 8 formed at the bottom of the cross head guide. Support member 4 is provided with an offset 55 shoulder 9. Arising from said shoulder is a flange 10 which is interiorly threaded at 11 to receive a tubular housing 12.

Within housing 12 and resting on shoulder 9 is a cast iron spool 13. A spool 14 60 is located within tubular housing 12 and is spaced from spool 13 by means of an insulating cylinder 15. Spools 13 and 14 are provided with flanges 16, 17, 18 and 19 and between these flanges insulated copper wire 65 is wound forming coils 20, 21 and 22.

The inner bores of the spools which are arranged axially in line are lined with a tubular brass liner 23 in which is placed a cylindrical core 24 formed to receive iron 70 or silicon steel (laminated if preferred) and which is reduced at its lower end 25 and is threaded into a cylindrical extension 26 of cross head 6. Cross head 6 is preferably made of non-magnetic material such as 75 phosphorous bronze and support member 4 is preferably made of steel. A brass plate 27 lies between the upper surface of shoulder 9 and the lower face of flange 16 of spool 19 so as to form a magnetic brake. 80 The spools 13 and 14 as well as insulating spacer cylinder 15 are held in place within tubular member 12 by means of a locking ring 28 which is threaded into the upper end of tubular member 12 and bears on the 85 upper surface of flange 19. Resting on flange 19 within locking ring 28 is a cylinder 29 preferably formed of insulating material such as bakelite. An annular plate 30 of the same material is supported by cylinder 29. A key cylinder 31 formed of insulating material rests on locking ring 28 and is provided with an annular shoulder 32 which rests on annular plate 30 and holds the same in place. Another annular plate 90 33 of insulating material rests on the top of insulating cylinder 31 and a head 34 preferably formed of steel is threaded into the upper end of tubular member 12 at 35.

The inner surface of the head member at 36 100 snugly fits the outer surface of insulating cylinder 31 and the head is provided with

an annular shoulder 37 which bears on the top of insulating plate 33. The head holds all of the insulating plates and cylinders described firmly in place.

5 An annular plate 38 of similar insulating material is arranged to reciprocate between plates 30 and 33 and is provided with and has embedded in its upper surface 4 concentric copper rings 39, 40, 41 and 42. These 10 rings stand in line with corresponding rings embedded in the lower face of disk 33 and these rings are numbered 43, 44, 45 and 46, respectively. The outer cylindrical surface of floating disk 38 is provided with an annular copper ring 47 which is adapted to make contact with an annular ring 48 embedded in the inner surface of cylinder 31. Ring 48 is of such length that ring 47 will always make contact with it in whatever 20 position disk 38 stands.

The upper surface of annular insulating disk 30 is provided with four concentric copper rings 50, 51, 52 and 53 and two concentric copper rings 54 and 55 embedded 25 in the lower face of floating disk 38 are adapted when disk 38 is in its lowermost position to connect together rings 50 and 51 and rings 52 and 53.

30 The outer end of core 24 is centrally bored out to form a cylindrical chamber 56 for the reception of a plunger 57 and a coil spring 58 lying within the bore and below plunger 57 tends to yieldingly hold said plunger at the limit of its outward stroke.

35 Insulating disk 30 at its center is provided with an opening 60 through which plunger 57 is adapted to pass when the core 24 is at the uppermost limit of its travel and floating disk 38 is provided with a centrally located metal contact plate 61 with which the plunger is adapted to contact when it raises disk 38 upon the upward movement of core 24 against the stress of a coil spring 62 which is located between 40 the upper surface of floating disk 38 and head 34 of the device. A central boss 63 lies within coil spring 62 and holds the same in place.

50 Floating disk 38 at its center is provided with an air duct 64 which passes through the plate from top to bottom and a non-return valve 65 is provided on the head in order to allow air to pass into the interior of the device. The non-return valve 55 prevents the escape of air from the interior. The interior of the device provides an air chamber A between plate 30 and the upper face of core 24 and another air chamber B between the upper part of head 34 and the 60 upper face of plate 33 and duct 64 passes these two air chambers in communication. These air chambers serve as an air cushion chamber and cushion the upward strokes of core 24.

A binding post 66 extends through head 34 and makes contact with the outer surface of copper ring 48. The binding post is provided with an insulating bushing 67 to insulate it from the head. Outer cylinder 12 is preferably provided with annular radiating flanges 70.

75 By referring to the diagram it will be seen that ring 41 is electrically connected to ring 47 by means of a wire 71. Ring 61 is connected to metallic disk 69 by means of a wire 72 and ring 40 is also connected to disk 69 by means of a wire 73. Ring 39 is connected by means of a wire 74 with contact ring 47. The wiring of diagram Fig. 3 is such that when switch plate 38 is in the position shown in the drawings coils 20, 21 and 22 will operate in series and when switch plate 38 is raised by core 24 a plunger 57 so as to contact with the contact rings of plate 33 the coils 20, 21 and 22 will operate in parallel. 80 Binding post 66 is arranged to be connected to a source of current supply 81 such as a storage battery and the lower end 80 of coil 20 is ground on the frame of the vehicle. Plunger 57 which is also ground on the frame of the vehicle by contacting with disk 61 grounds said disk. A switch 82 is provided in the line between the battery 81 and the device in order that the current may be cut off whenever the vehicle is to stand for any appreciable time.

85 When the vehicle is standing with the current cut off contact plate 38 will be held in contact with plate 33 and when switch 82 is closed the coils 20, 21 and 22 will operate in parallel to lift the load platform and as soon as the load platform has been lifted far enough to allow contact plate 38 to move away from contact plate 33 into contact with plate 30 and the coils then operating in 90 series will yieldingly sustain the platform. The arrangement is such that the core 24 will tend to hold its mid position as shown in Fig. 1. The time during which the coils will operate in parallel may be varied by 100 varying the length of plunger 24 as well as the length of coil spring 58.

105 Having thus described my invention what I claim is—

1. The combination with a vehicle frame and the steel springs, of electromagnetic means between said frame and one end of each of said steel springs and constructed to operate in series therewith in resiliently supporting said frame.

110 2. A spring support for vehicles, comprising a leaf spring and an electromagnetic spring connected to one end of said leaf spring and arranged to operate in series therewith to support a load.

115 3. The combination with a vehicle frame, of a leaf support spring for said frame and an electromagnetic spring between said leaf

spring and said frame and arranged to serially augment said leaf spring in resiliently supporting said frame.

4. The combination with a vehicle frame, of magnet coils carried by said frame, a leaf spring, a magnet core secured to one end of said leaf spring and arranged to operate in connection with said coils to form a magnetic spring operating in series with said leaf spring.

In testimony whereof, I have hereunto subscribed my name this 2nd day of November, 1918.

RICHARD LIEBAU.
